(57) **CLAIM**

The ornamental design for an orthopaedic bone plate, as shown and described.

DESCRIPTION

FIG. 1 is a bottom perspective view of an orthopaedic bone plate according to the present invention.

FIG. 2 is a top perspective view thereof.

FIG. 3 is a top elevational view thereof.

FIG. 4 is a bottom elevational view thereof.

FIG. 5 is a right elevational view thereof.

FIG. 6 is a left side elevational view thereof.

FIG. 7 is a rear elevational view thereof.

FIG. 8 is a front elevational view thereof.

FIG. 9 is a top perspective view of an alternative embodiment of the present invention.

FIG. 10 is a bottom perspective view of the alternative embodiment.

FIG. 11 is a top elevational view of the alternative embodiment.

FIG. 12 is a bottom elevational view of the alternative embodiment.

FIG. 13 is a left side elevational view of the alternative embodiment.

FIG. 14 is a right side elevational view of the alternative embodiment.

FIG. 15 is a rear elevational view of the alternative embodiment; and,

FIG. 16 is a front elevational view of the alternative embodiment.

The broken line showing is for illustrative purposes only and forms no part of the claimed design.
